UNITED STATES PATENT OFFICE.

SAMUEL L. SHELLENBERGER, OF SOUTH McALESTER, OKLAHOMA, ASSIGNOR OF ONE-HALF
TO EDWIN D. CHADICK, OF SOUTH McALESTER, OKLAHOMA.

RAILWAY-SWITCH.

No. 875,959.

Specification of Letters Patent.

Patented Jan. 7, 1908.

Application filed January 11, 1907. Serial No. 351,876.

To all whom it may concern:

Be it known that I, SAMUEL L. SHELLENBERGER, a citizen of the United States of America, residing in South McAlester, in the 5 State of Oklahoma, have invented certain new and useful Improvements in Railway-Switches, of which the following is a full, clear, and exact description, reference being had to the accompanying drawings, forming 10 part of this specification.

My invention relates to switches for railroad tracks and it has for its object to provide an efficient switch of this character without breaking or interrupting the continuity 15 of the rails of the main line track, whereby the rails of said main line track are caused to present as smooth track surfaces at the location of a switch as at any point aside from the switch.

20 Figure I is a top or plan view of a portion of my switch. Fig. II is a top or plan view of a continuation of the switch adjoining the part shown in Fig. I. Fig. III is a vertical cross section taken on line III—III, Fig. I. 25 Fig. IV is a longitudinal section taken on line IV—IV, Fig. I. Fig. V is a longitudinal section taken on line V—V, Fig. I. Fig. VI is a vertical cross section taken on line VI—VI, Fig. II. Fig. VII is a perspective 30 view of fragments of one of the platforms on which the swinging switch members operate and the forward end of one of the swinging switch members.

1 and 2 designate the rails of a main line 35 track which are unbroken and are not interfered with in any manner in the construction of my switch.

3 is an intermediate rail of a branch track located between the main line rails. This 40 intermediate rail terminates at 4 in juxtaposition with the main line rail 1, see Fig. I and at 5 in juxtaposition with the main line rail 2, see Fig. II. At the last named end of the intermediate branch rail is a crossing 45 block or rail section 6 that occupies a position alongside of the main line rail 2 and abuts against the end of the intermediate rail. The crossing block occupies a position 50 inside of the main track and its top is flush with the top of the main line rail 2 and as close to this rail as possible while permitting passage of car wheel flanges between said members. The block is securely spiked to the ties on which the main line rails rest and 55 it is preferably of inverted U-shape in cross

section, as seen in Fig. VI. 3', see Fig. II, is a branch rail located exterior of the main line track and terminating adjacent to the main line rail 2 and in line with the intermediate branch rail 3, see Fig. II. 60

7 is an outer branch track rail that leads to a point 8 and into juxtaposition with the main line track rail 2, as seen in Fig. I.

9 designates a platform located along-side of the main line track rail 1 at the inside of 65 the track and extending from the intermediate branch track rail 3. This platform is preferably of inverted U-shape in cross section, as seen in Fig. III, and in the top of it are transverse slots 10. The platform 9 is of 70 such height that its top occupies a position sufficiently beneath the tread of the main line rail 1 to permit the passage of truck wheel tread flanges above said platform. This platform is secured to the ties on which 75 the main track rails are laid by spikes and the leg of the platform that opposes the rail 1 is hooked thereunder, as seen at 11, Fig. III.

12 is a switch rail that is mounted on the platform 9 and provided with a tread flange 80 13 that is adapted to be moved into a position above the tread of the main line track rail 1. The switch rail 12 is connected at its end adjoining the intermediate branch track rail 3 to the platform 9 by a pivot bolt 14, 85 thereby providing for the desired movement of the switch rail to the main line track rail 1 in order that the wheels of the car truck may be guided from the main line track rail to the intermediate branch track rail or vice versa, 90 without there being any break in the main line track rail. The flange of the switch rail is sloped at 15, see Fig. IV, adjacent to the free end of said switch rail in order that the truck wheels may ride onto said flanges or 95 off of it without jarring action. At the free end of the switch rail 12 is a retaining tongue 16, see Figs. I, IV, and VII, that is turned under the top of the platform 9 and serves to hold the switch rail in a depressed position 100 while permitting the shifting thereof to and from the main line track rail 1.

17 designates a platform located at the exterior of the main line track and along-side of the track rail 2, the said platform extending 105 from the outer branch track rail 7. This platform is of inverted U-shape in cross section and is of a construction similar to the platform 9, being provided with transverse slots 18 located in the top thereof and having 110

its inner leg hooked under the flange of the rail 2 at 19, see Fig. III. The platform 17 preferably differs, however, from the platform 9 in being of a height approximately 5 the same as the height of the main line track rails.

21 is a switch rail loosely mounted on the platform 17 and provided with a wheel tread flange 22. The end of the switch rail 21 that 10 adjoins the end of the outer branch track rail 7 is connected to the platform 18 by a pivot bolt 23, thereby permitting lateral movement of the switch rail in order that it may be carried over the main line track rail 2 15 to bring its flange into alignment with the tread of said track rail and provide for the travel of car truck wheels from the main line track rail to the branch track rail or vice versa, without the main line track rail being 20 broken. The flange of the switch rail 21 is provided with a slope 24, see Fig. V, at the free end of said rail to prevent jarring action in the travel of the truck wheels onto the switch rail or off of it, according to the direction 25 in which the car is moving. At the free end of the switch rail 21 is a retaining tongue 25 that is turned under the top of the platform 17 on which said switch rail rests and which has a function similar to that of the 30 tongue 16 carried by the switch rail 12.

26 designates connecting rods that unite the switch rails 12 and 21, they being pivotally connected to said rails by bolts 27.

28 is a platform similar in construction to 35 the platforms 9 and 17, and located alongside of the main line track rail 2 at the outside of the main track and which extends from the branch rail 3'. This platform has its inner leg hooked under the outer flange of 40 the track rail 2, at 29, see Fig. VI, and the top of the platform is slotted similarly to the platforms 9 and 17.

30 designates a crossing switch rail that is provided with a tread flange 31 and is pivotally connected at 32 to the platform 28 at 45 its end adjoining the branch track rail 3'. The crossing switch rail is therefore movably mounted on said platform in a manner to permit of its being moved across the main 50 line track rail 2 to provide a treadway for the car truck wheels leading from the intermediate branch track rail 3 and crossing block 6 to the branch track rail 3' or vice versa, without breaking the main line track rail 2. The 55 crossing switch rail 30 is provided with a retaining tongue 33 located at its free end and engaging the top of the platform on which said rail rests and which has the same function as the retaining tongues 16 and 25 of the 60 switch rails 12 and 21.

The movable switch rails of my switch may be operated by any suitable mechanism to shift them into or out of switching positions.

65 The form of operating mechanism I have

shown comprises a switch operating lever 34 that is connected through the medium of a series of rocking levers 35 to a throw rod 36 united to one of the bolts that connect the connecting rods 26 to the switch rails 12 and 21 and also comprises rocking levers 37 that are joined by a throw rod 38 to the crossing switch rail 30 by a pivot bolt 39.

I claim:

1. In a railroad switch, the combination 75 with main line track rails, of branch track rails terminating in juxtaposition to said main line rails, platforms of inverted U-shape in cross section, and a pair of movable switch rails mounted on said platforms and adapted to be shifted into position above said main track rails, substantially as set forth.

2. In a railroad switch, the combination 85 with a pair of main track rails, of a pair of branch track rails terminating in juxtaposition to said main track rails, flanged platforms of inverted U-shape in cross section, and a pair of switch rails pivotally connected to said flanged platform at terminations 90 of said branch rails and movable on the flanged platform into positions above said main track rails, substantially as set forth.

3. In a railroad switch, the combination 95 with a pair of main track rails, of a pair of branch rails terminating in juxtaposition to said main track rails, platforms of inverted U-shape in cross section, and a pair of switch rails pivotally connected to said platform at terminations of said branch rails and movable 100 on the platform into positions above said main track rails; said switch rails being provided with flanges, substantially as set forth.

4. In a railroad switch, the combination 105 with a pair of main track rails, of a pair of branch track rails terminating in juxtaposition to said main track rails, platforms of inverted U-shape in cross section, and a pair 110 of switch rails pivotally connected to said platform at terminations of said branch rails and movable on the platform into positions above said main track rails; said switch rails being provided with flanges having sloping portions at the free ends of the 115 rails, substantially as set forth.

5. In a railroad switch, the combination 120 with a pair of main track rails, of a pair of branch track rails, platforms of U-shape in cross section located adjacent to said main track rails, and having legs hooked under said main track rails, and switch rails pivotally mounted upon said platforms and movable to and from said main track rails, substantially as set forth.

6. In a railroad switch, the combination 125 with a pair of main track rails, of a pair of branch track rails, platforms located adjacent to said main track rails, and switch rails pivotally mounted upon said platforms 130

- and movable to and from said main track rails; said switch rails being provided at their free ends with retaining means engaging said platforms, substantially as set forth. 25
7. In a railroad switch, the combination with a pair of main track rails, of a pair of branch track rails, platforms located adjacent to said main track rails, and switch rails pivotally mounted upon said platforms and movable to and from said main track rails; said switch rails being provided with retaining tongues engaging said platforms, substantially as set forth. 30
- 15 8. In a railroad switch, the combination with a pair of main track rails, of a pair of branch track rails terminating in juxtaposition to said main track rails, inverted U-shaped platforms located adjacent to said main track rails and having legs provided 35 with hooked engagement with the flanges of said main track rails, and switch rails pivoted to said platforms and adapted to be moved into a position above the adjacent main track rail, substantially as set forth. 40

said main track rails, and switch rails pivoted to said platforms and adapted to be moved into position above said main track rails, substantially as set forth. 25

9. In a railroad switch, the combination with a pair of main track rails, of branch track rails extending into juxtaposition with said main track rails, and crossing means located in the line of one of said branch track rails; said crossing means comprising a crossing block of inverted U-shape in cross section a platform of inverted U-shape in cross section and a switch rail pivoted to said platform and adapted to be moved into a position above the adjacent main track rail, substantially as set forth. 35
